CIRCUIT MAKING AND BREAKING
MECHANISM

Allan F. Lake, Oakland, Calif.

Application October 5, 1927. Serial No. 224,118

7 Claims. (Cl. 172—126)

This invention relates to a direct current circuit making and breaking mechanism to be used in conjunction with electric bells, gongs, vibrators, and other electro-magnetic actuated devices.

The object of the present invention is to generally improve and simplify the construction and operation of devices of the character described and especially to provide a simple form 10 of direct current making and breaking mechanism whereby the circuit through the coil of a bell or like electro-magnetic actuated device may be automatically controlled.

The invention is shown by way of illustration 15 in the accompanying drawing in which:

Fig. 1 is a central vertical longitudinal section of an electro-magnetic actuated bell or gong showing the application of the invention,

Fig. 2 is a similar section showing the circuit 20 making and breaking mechanism in a position where the circuit is broken.

Referring to the drawing in detail, A indicates a base member upon which is mounted a coil B, a striker or armature C, and a bell D. The 25 coil illustrated in the present instance is of the solenoid type. It consists of a spool 2 upon which the coil B is wound. Mounted interior of the spool is a tube 3 constructed of a non-magnetic material, as is usually the case, this tube being 30 secured in place by a cap 4 at one end and a sleeve 5 at the opposite end. Mounted within the solenoid tube is a stationary core member 6 and reciprocally mounted within the solenoid tube is the movable core member or 35 armature previously referred to and indicated at C. This movable core member consists of an enlarged central guide portion 7, an upper reduced end section 8, and a lower reduced end section 9 which forms the striker. The upper 40 reduced portion 8 carries a helical compression spring 10 and a similar spring 11 is interposed between the sleeve 5 and the enlarged portion 7, the tension of the spring 11 being just sufficient to support the weight of the armature or 45 striker. Secured to the upper end of the spool or coil B is a pole piece 12 and also secured to the upper end is a frame piece 13 which forms a support for the circuit making and 50 breaking mechanism generally indicated at E. This mechanism consists of a stationary conductor strip 15 carrying a stationary contact 16. This conductor strip is secured to the frame piece 13 by a post and insulating washers indicated at 17. This post also supports a spring 55 arm 18 and this in turn carries a movable

contact member 19 and an armature member 20. The solenoid magnet is provided with two terminal posts 21 and 22 which may be connected with a direct current circuit in the usual manner. The terminal 22 is connected with the upper end of the coil B through means of wire 23. The lower terminal of the coil is connected through means of wire 24 with the lower end of the vibrator arm 18, the opposite terminal 21 being connected through wire 25 with the lower end of the conductor strip 15. A circuit will in this manner be closed through the coil B when the contacts 16 and 19 engage, as shown in Fig. 1, and it is automatically broken when they are separated, as shown in Fig. 2.

Practically all of the electro-magnetic devices in use to-day whether bells, vibrators or whatever the case may be, employ a coil and a movable armature. The armature in turn carries a striker and it also invariably carries the circuit 70 making and breaking mechanism. It is here that the present invention distinguishes over ordinary practice, as it will be noted that the circuit making and breaking mechanism operates entirely independently of the armature or striker, 75 and similarly that the striker or armature operates entirely independently of the circuit making and breaking mechanism. In other words, two armatures are employed, a main armature indicated at 7 and a second armature as 80 indicated at 20, both armatures being energized 85 or actuated by the common coil B and the secondary armature in turn actuating or controlling the circuit through the coil.

The spring tension of the vibrating arm 18 is 90 such that the contacts will normally close, as shown in Fig. 1. When they so close a circuit is established in the coil and the magnetic flux thus set up will simultaneously actuate both the main armature and the secondary armature. 95 The main armature will then be raised to the position shown in Fig. 2 where it places the spring 10 under compression. The secondary armature, together with the vibrating arm 18 supporting the same, will assume the position shown 100 in Fig. 2 as it will be attracted by the pole piece 12. The moment it is so attracted, the electric circuit through the coil is broken, the flux ceases, and the main armature will be projected with considerable force against the bell or gong, first 105 due to the projecting action of the helical spring 10 and secondly, due to the gravitational movement of the main armature. The secondary armature, together with the vibrating arm 18 is 110 simultaneously returned to the position shown

in Fig. 1 and the electric circuit through the coil is again closed and the cycle of operation is thus repeated and repeated as long as the current is passing through the terminals 21 and 22. It should be noted that until the armature 7 is drawn upwardly there is an air gap between it and the stationary armature 6. Hence the magnetic field is weaker than it is after the armature 7 has been drawn into contact with the armature 6. The tension of spring 18, upon which the armature 20 is supported, is such that until the strength of the field is increased by upward movement of the armature 7, the armature 20 is not moved to open the make and break device. The result is that a relatively slow action is given to the armature 7 and striker 9 carried thereby. Such action is desirable to bring out the full resonance of the bell D. Another important feature which should be particularly noted is the fact that the secondary armature does not move into engagement with the pole piece 12 and as such will not be subjected to the severe vibrations usually encountered. The bell mechanism or armature C has no mechanical connection with the contacts or circuit breaking mechanism, thus further safeguarding or protecting the contacts and spring from excess vibration and hammer action. The circuit breaker, furthermore, forms a complete, independent unit and receives only sufficient magnetic flux to insure its positive operation. The contacts may thus be made large, and sparking is reduced to a minimum due to the small amount of iron subjected to magnetic influence.

While the circuit making and breaking mechanism is here shown as used in conjunction with an electric bell or gong, it may obviously be used on any electro-magnetic vibrating or reciprocating device which is actuated by a direct current.

While certain features of the present invention are more or less specifically described, I wish it understood that various changes may be resorted to within the scope of the appended claims. Similarly, that the materials and finishes of the several parts employed may be such as the manufacturer may decide or varying conditions or uses may demand.

Having thus described my invention, what I claim and desire to secure by Letters Patent is:—

1. An electro-magnetic device of the character described comprising a coil, an armature member reciprocally mounted within the coil, and a second armature mounted for oscillation adjacent the coil and adapted to operate a make and break device for alternately energizing and de-energizing the coil whereby the first named armature will be reciprocated therein, the motion of said first and second named armatures being synchronized and so correlated that the position of the first named armature within the coil will control the degree of magnetism affecting the second named armature.
2. An electro-magnetic device comprising a coil, an armature member reciprocally mounted within the coil and adapted to be actuated thereby, a

make and break device for alternately energizing and de-energizing said coil, said make and break device being actuated by a second armature mounted for oscillating movement exterior of the coil, and a pole piece disposed adjacent the free end of the second armature at a point where the second armature can move into alignment with the pole piece without engaging the same, said pole piece also being energized by said coil.

3. An electro-magnetic device of the character described comprising a coil, a reciprocable armature adapted to be magnetically attracted upon energization of the coil, an oscillatory armature adapted to be attracted by energization of the coil, a make and break device actuated by the oscillatory armature, and an electric circuit for energizing the coil and including said make and break device, said reciprocable armature being adapted to reciprocate within the coil toward and away from the magnetic field thereof whereby its position will affect the degree of magnetism exerted upon said oscillatory armature.

4. An electro-magnetic device of the character described, comprising a coil, an armature member within the coil and mounted for reciprocal movement into and out of the coil, and a second armature mounted adjacent the coil and adapted to open and close a switch in a circuit for energizing the coil, said second armature normally holding said switch closed and being moved by the magnetic field of the coil to open the switch upon the event of the first armature being moved into the coil.

5. An electro-magnetic device of the character described, comprising a coil, an armature movable into and out of the coil, a second armature controlling the operation of a make and break device in a circuit for energizing the coil, said second armature normally closing said circuit and being caused to open the circuit only when the magnetic field of the coil is intensified by the first armature being drawn into the coil.

6. An electro-magnetic device of the character described comprising a coil, an armature movable into and out of the coil, a second armature controlling the operation of a make and break device in a circuit for energizing the coil, a spring supporting said second armature and normally retaining it in a position closing said circuit, the tension of said spring being such that the armature will be moved to open said circuit only when the magnetic field of the coil is intensified by the first armature being drawn into the coil.

7. An electro-magnetic device of the character described comprising a coil, an armature movable into and out of the coil, a second armature controlling the operation of a make and break device in a circuit for energizing the coil, resilient means normally urging the second armature to a circuit closing position, the tension of said resilient means being such that the armature will be moved to open said circuit only when the magnetic field of the coil is intensified by the first armature being drawn into the coil.
